EMIL STUMPF, OF ELBERFELD, GERMANY.

DESIGN FOR A FABRIC.

Design No. 19,167, dated June 18, 1889.

UNITED STATES PATENT OFFICE.

EMIL STUMPF, OF ELBERFELD, GERMANY.

DESIGN FOR A FABRIC.

SPECIFICATION forming part of Design No. 19,167, dated June 18, 1889.

Application filed May 23, 1889. Serial No. 311,882. Term of patent 3½ years.

To all whom it may concern:

Be it known that I, EMIL STUMPF, of the firm of Stumpf, Gross & Co., of Elberfeld, Germany, have invented and produced a new and original Design for Fabrics, of which the following is a full, clear, and exact description,

Reference is to be had to the accompanying photograph, forming part of this specification, which represents a plan view of the design.

10 The design consists of a basket-like figure A, side figures B and B', representing, respectively, flowers of the daisy type, and buds appearing to drop down from the basket figure.

Above the basket figures C and C' are arranged side by side, drawn in imitation of an open flower of the rose type, and over the figures C C' a single figure D is drawn, representing a group of leaves and a flower of the lilac type, and at each side of the upper figure a single figure E and E' is respectively

arranged, representing small roses and buds, the grouping of the flower figures in the basket figure being pyramidal.

At each side of the center figure, above described, a scroll leaf-like figure G is arranged, and at top and bottom of the central figure a double figure H is produced, representing two of the side figures united by a transversely-drawn scroll, above which and between the main scrolls of the figure a flower is made to appear.

The figures M are simply repeats of the figures heretofore described.

I claim—

15 A design for fabrics, substantially as shown and described.

EMIL STUMPF.
